UNITED STATES PATENT OFFICE

WILLIAM J. DE WITT, OF AUBURN, NEW YORK, ASSIGNOR TO SHOE FORM CO., INC.,
OF AUBURN, NEW YORK, A CORPORATION OF NEW YORK

SHOE FORM

Application filed April 25, 1929. Serial No. 357,946.

This invention relates to an improvement in a shoe form and more particularly in a shoe form comprising a hollow toe member of resilient material and a cross bar connecting the walls of such member. It is particularly desirable in such shoe forms that means be provided whereby the walls of the members may be expanded or contracted in order to increase or decrease the width of the member.

10 The object of the present invention is to provide a shoe form in which such increase or decrease in width of the toe member may be quickly and easily attained and in which, furthermore, the member will be held in the 15 contracted position but be capable of being expanded to the desired width while the form is either within or outside the shoe.

20 Two of the embodiments of this invention are illustrated in the accompanying drawings 20 in which.

Fig. 1 is a bottom plan view of one type of shoe form embodying this invention, the parts being shown by full lines in the contracted position and by dotted lines in the expanded 25 position;

Fig. 2 is a similar view of another type of shoe form embodying this invention, the parts being shown by full and dotted lines in the contracted and expanded conditions; and

30 Fig. 3 is a sectional view of the shoe form illustrated in Fig. 1 taken along the line 3—3 thereof.

The shoe form to which this invention is directed comprises a toe member 10 and a 35 cross bar 11. The member 10 is hollow in conformation as shown particularly in Fig. 3 being made of thin resilient material such as, for example, sheet celluloid and comprising an outer wall 15 and an inner wall 16.

40 Each wall has at the bottom an inwardly projecting flange indicated on the drawing as 17 and 18 respectively and in the flange 17 of the outer wall 15 is formed a slot 19 curved or arcuate as shown in Fig. 1.

45 The cross bar 11 is pivotally secured intermediate its length to the flange 18 in any suitable way as by a rivet 20. The end 21 of the cross bar is attached to a button 22 which extends through the slot 19, the ends of the 50 button 22 being expanded at 23, 24 so that the

button will remain in the slot 19. The cross bar 11 is looped around the rivet 20 (see Fig. 3) and its end 25 extends forwardly of the rivet and rests against the wall 16 of the toe member. Since the cross bar 11 is made of resilient material, preferably wire, the end 25, bearing against the wall 16, normally acts to hold the end 21 of the cross bar in the full line position shown in Fig. 1, the button 22 being at the rearward end of the slot 19. When the cross bar 11 is forced forward into the toe member 10, turning on its pivot 20, the button 22 traveling in the slot 19 reduces the width of the toe member so that when the button 22 is at the other end of the slot the walls of the toe member are contracted as shown on dotted lines.

In using this shoe form the cross bar is first manipulated to bring the toe member into the contracted position shown on dotted lines and the form is then inserted into the shoe and allowed to expand to the limit set by the walls of the shoe. The end 25 of the cross bar normally tends to carry the cross bar back into the full line position, in which the member is fully expanded, thus insuring that the toe of the shoe is held plumped out to its proper condition and giving to it the appearance it will assume, when on the foot of the wearer.

The type shown in Fig. 2 is similar and will not therefore be described in detail, the parts of the figure embodiment being indicated by numerals which are primes of the numerals used in the description of the Fig. 1 embodiment. It will be noted, however, that the end 25' of the cross bar 11' extends rearwardly from the rivet 20' to which the cross bar is pivotally secured and consequently that the button 22' will normally be held by the cross bar 11' at the forward end of the slot 19'.

The various elements of the Fig. 2 embodiment function in the same manner as the corresponding elements of the Fig. 1 embodiment and it is believed that there is no necessity of describing such actions in detail. It will be noted, however, that the cross bar 11' travels rearwardly to contract the member 10' and consequently when the toe member 10' is removed from the shoe the exertion of a pull upon the cross bar 11', either manually

or by means of a suitable tool or by means of a back stay which is commonly used in shoe forms of this type, will draw the cross bar back thus contracting the walls of the toe member 10'.

While two embodiments have been shown and described these embodiments were selected for the purpose of illustration only and applicant is not limited thereto since other 10 embodiments might be made without departing from the spirit and scope as set forth in the following claims.

I claim:

1. A shoe form comprising a hollow toe 15 member of resilient material, a cross bar connecting the walls of the toe member, said cross bar being pivotally attached to one wall and slidably attached to the other wall so that in one position of the cross bar the walls are 20 expanded and in another position thereof the walls are contracted and means normally acting to hold the cross bar in the position in which the walls are expanded.

2. A shoe form comprising a hollow toe 25 member of resilient material, a cross bar connecting the walls of the toe member, said cross bar being pivotally attached to one wall and slidably attached to the other wall so that in one position of the cross bar the walls are 30 expanded and in another position thereof the walls are contracted and means normally acting to hold the cross bar in one of said positions and being yieldable to permit the cross bar to take the other position.

3. A shoe form comprising a hollow toe 35 member of resilient material, a cross bar connecting the walls of the toe member, said cross bar being pivotally attached to one wall and slidably attached to the other wall so that in one position of the cross bar the walls are 40 expanded and in another position thereof the walls are contracted and an extension of said cross bar bearing against one wall of the toe member to hold the cross bar normally in one of said positions.

4. A shoe form comprising a hollow toe 50 member of resilient material, a cross bar connecting the walls of the toe member, said cross bar being pivotally attached to one wall and slidably attached to the other wall so that in one position of the cross bar the walls are 55 expanded and in another position thereof the walls are contracted and an extension of said cross bar bearing against one wall of the toe member to hold the cross bar normally in the position in which the walls are expanded.

5. A shoe form comprising a hollow toe 60 member of resilient material, a cross bar connecting the walls of the toe member, said cross bar being pivotally attached to one wall and slidably attached to the other wall so that in one position of the cross bar the walls are 65 expanded and in another position thereof the walls are contracted and an extension of

the pivoted portion of said cross bar bearing against one wall of the toe member to hold the cross bar normally in one of said positions.

6. A shoe form comprising a hollow toe 70 member of resilient material, a cross bar connecting the walls of the toe member, said cross bar being pivotally attached to one wall and slidably attached to the other wall so that in one position of the cross bar the walls are expanded and in another position thereof the walls are contracted and an extension of the pivoted portion of said cross bar bearing against one wall of the toe member to hold the cross bar normally in the position in which the walls are expanded.

7. A shoe form comprising a hollow toe 75 member of resilient material having flanges on the walls thereof, one of said flanges having a slot therein, a cross bar pivotally attached to the unslotted flange and having a 80 slidable engagement with the slot in the other flange of the toe member so that in one position of the cross bar the walls are expanded and in another position thereof the walls are contracted and means normally acting to hold the cross bar in that position in which the walls are expanded.

8. A shoe form comprising a hollow toe 85 member of resilient material having flanges on the walls thereof, one of said flanges having a slot therein, a cross bar pivotally attached to the unslotted flange and having a 90 slidable engagement with the slot in the other flange of the toe member so that in one position of the cross bar the walls are expanded and in another position thereof the walls are contracted and means normally acting to hold the cross bar in one of said positions and being 95 yieldable to permit the cross bar to take the other position.

9. A shoe form comprising a hollow toe 100 member of resilient material having flanges on the walls thereof, one of said flanges having a slot therein, a crossbar pivotally attached to the unslotted flange and having a 105 slidable engagement with the slot in the other flange of the toe member so that in one position of the cross bar the walls are expanded and in another position thereof the walls are contracted and an extension of the pivoted portion of said cross bar acting normally to hold the cross bar in one of said positions and being 110 yieldable to permit the cross bar to take the other position.

10. A shoe form comprising a hollow toe 115 member of resilient material having flanges on the walls thereof, one of said flanges having a slot therein, a cross bar pivotally attached to the unslotted flange and having a 120 slidable engagement with the slot in the other flange of the toe member so that in one position of the cross bar the walls are expanded and in another position thereof the walls are contracted and an extension of the pivoted 125 portion of said cross bar

portion of said cross bar bearing against the wall of the toe member and acting normally to hold the cross bar in that position in which the walls are expanded.

5 11. A shoe form comprising a hollow toe member of resilient material having flanges on the walls thereof, one of said flanges having a slot therein, a cross bar pivotally attached to the unslotted flange, a button in said slot to which button one end of the cross bar is secured and means associated with said cross bar for holding the button normally at one end of said slot.

10 12. A shoe form comprising a hollow toe member of resilient material having flanges on the walls thereof, one of said flanges having a slot therein, a cross bar pivotally attached to the unslotted flange, a button in said slot to which button one end of the cross bar is secured and yielding means associated with said cross bar for holding the button normally at one end of said slot whereby the walls of the toe member are expanded and for resisting the movement of the button in the slot by 20 which the walls of the toe member would be contracted.

25 13. A shoe form comprising a hollow toe member of resilient material having flanges on the walls thereof, one of said flanges having a slot therein, a cross bar pivotally attached to the unslotted flange, a button in said slot to which button one end of the cross bar is secured and an extension of the pivoted portion of the cross bar acting upon the cross bar to hold the button normally at one end of the slot.

30 14. A shoe form comprising a hollow toe member of resilient material having flanges on the walls thereof, one of said flanges having a slot therein, a cross bar pivotally attached to the unslotted flange, a button in said slot to which button one end of the cross bar is secured and an extension of the pivoted portion of the cross bar bearing against one wall of the toe member and acting upon the cross bar to hold the button normally at one end of the slot.

35 15. A shoe form comprising a hollow toe member of resilient material having flanges on the walls thereof, one of said flanges having a slot therein, a cross bar pivotally attached to the unslotted flange, a button in said slot to which button one end of the cross bar is secured and an extension of the pivoted portion of the cross bar bearing against one wall of the toe member, said extension acting upon the cross bar to hold the button normally at one end of the slot whereby the walls of the toe member are expanded and yieldingly resisting the movement of the button in the slot by which the walls of the toe member would be contracted.

Signed by me at Auburn, N. Y., this 18th day of April, 1929.

65 WILLIAM J. DE WITT.
